UNITED STATES PATENT OFFICE.

NILS ANDERSON, OF OMAHA, NEBRASKA.

PIPE-LAYING MACHINE.

1,028,523.

Specification of Letters Patent.

Patented June 4, 1912.

Application filed May 12, 1911. Serial No. 626,825.

To all whom it may concern:

Be it known that I, NILS ANDERSON, a citizen of the United States, and a resident of Omaha, in the county of Douglas and State 5 of Nebraska, have invented certain new and useful Improvements in Pipe-Laying Machines, of which the following is a specification.

My invention relates to machines for forcing metal pipes through the ground in order 10 to avoid the necessity of digging continuous trenches or tunnels in which to lay them.

It is the object of my invention to provide 15 in a machine of this class an improved means for gripping the pipe, whereby the gripping pressure upon the pipe is automatically proportioned to the force necessary to push it through the ground.

20 A further object of my invention is to provide means for guiding the pipe, and means for imparting a slight rotary movement thereto as it advances through the ground.

A further object of my invention is to 25 provide a pipe-gripping device which may be set over the pipe after the same is in position to be driven, thus avoiding the necessity of passing the pipe endwise through the device before placing it in position.

30 In the accompanying drawings Figure 1 is a plan view of a machine embodying my invention, Fig. 2 is a side elevation of the same, Fig. 3 is an end view thereof, and Fig. 4 is a detail of one of the gripping jaws.

35 In carrying out my invention I provide a frame consisting of the base-bars 1, the upper tie-bars 2, the arched cross-bars 3, and the lower cross-bar 4, all of which are permanently secured together by suitable rivets 40 or bolts. The base-bars 1 have formed at each end thereof a loop or eye 5 through which stakes may be driven to secure the frame in position in the trench from which the pipe is to be driven. At the center of the 45 upper or horizontal transverse portions of the arch-bars 3 the same are bowed slightly downward to form a channel for receiving and guiding the pipe A. On the lower cross-bar 4 are secured upwardly extending lugs 6

50 adapted to receive between them the lower ends of the forked lever or yoke 7, of which the said ends carry pins 8 adapted to fit removably into the notches in the lugs. A removable lever-handle is provided having

at the end a socket adapted to fit over the 55 upper end 9 of the yoke, as indicated by dotted lines in Fig. 2.

The yoke 7 is connected by means of the links 10 with the ends of the bar 11, and to said bar are pivotally connected the rearward ends of the toggle-links 12 and 13. The forward ends of said links are pivotally connected with the ends of the toggle-levers 14 and 15, and the latter are pivoted upon the tie-bar 16 of which the end portions are 65 bent to form rectangular hooks passing around the outer sides of the toggle-levers as shown in Fig. 3. On the inner sides of the toggle-levers at the front ends thereof are formed recesses in which are pivotally 70 disposed the toothed jaw-pieces 17, the same being permitted to have a rocking movement sufficient to enable the toothed faces thereof to lie parallel with each other when the levers are spread apart more or less to accommodate different sizes of pipes. A coil spring 18 has the ends thereof connected with the bars 11 and 16 and normally pulls 75 said bars toward each other, thus tending to spread the toggle-links and levers outwardly and to close the jaw-pieces in upon 80 the pipe.

In the use of the machine the frame is secured in position in the trench by driving down stakes through the eyes 5 formed at 85 the ends of the base-bars 1. The pipe A is then laid upon the frame and the yoke 7 is set down over the pipe, the forked portion straddling the same as shown. The connected ends of the toggle-links and levers are then 90 pushed toward each other so as to open the jaws sufficiently to enable them to pass down over the pipe, while the bars 11 and 16 rest upon the upper side of the pipe and the toggle-links 12 and 13 rest upon the transverse 95 portion of the front cross-bar 3. The removable lever handle is then set over the upper end 9 of the yoke 7 and the yoke is moved back and forth by means of said handle. The front end of the pipe may be 100 provided with a sharp pointed plug to facilitate its passage through the ground. The movement of the pipe is further facilitated by imparting to it a slight rotary movement, and such movement is caused by 105 the following means: The toggle-links 12 and 13 are made of greater depth at one end than at the other, the thick end of the link

12 being shown in Fig. 2 as at the rear end thereof. The other link 13 has the thick end at the front, and the lower side of each link normally rests upon the top of the 5 arched cross-bar 3. The lower sides of the links thus form approximately helical lines about the axis of the pipe A, so that as the toggle device is moved back and forth it is rotated slightly in alternate directions. 10 During the forward movement of the toggle device the pressure from the bar 11 upon the links 12 and 13 tends to spread said links and the levers outwardly and thus to close the jaws upon the pipe so that the pipe 15 is gripped with a force proportional to the force necessary to push it through the ground. During the rearward movement of the toggle device the pull upon the links tends to open the jaws so that they will 20 readily slide back over the pipe. After a section of the pipe has been pushed forward as far as possible, the yoke and toggle device may be lifted off the frame, another piece of pipe laid thereon and connected 25 with the first section, after which the toggle device and yoke may be replaced on the frame over the pipe and the pushing operation continued as at first.

By making the frame, the toggle device 30 and the lever-handle separable, the handling of the machine in moving it from place to place is greatly facilitated, and, owing to the fact that the toggle device may be placed over the pipe after it is laid upon the frame, 35 the machine may be operated with facility in trenches no longer than the lengths of pipe to be driven.

Now, having described my invention, what I claim and desire to secure by Letters Patent is:

1. In a machine of the class described, a frame, a pipe-gripping device adapted to be placed over a pipe from one side thereof, and a lever fulcrumed on the frame and

connected with the gripping device for actuating the same.

2. In a machine of the class described, a frame adapted to support a pipe, a forked lever fulcrumed on the frame and adapted to straddle the pipe, and a toggle device 50 having jaws adapted to grip the pipe, the toggle device being connected with the forked lever and being open at one side so as to adapt it to straddle the pipe from the same side as the forked lever.

3. In a machine of the class described, a pair of transverse bars, resilient means connecting the same, a pair of links connected with one of said transverse bars, a pair of levers fulcrumed on the other transverse 60 bar and each connected at one end with one of the links, and pipe-gripping jaws carried at the other ends of the levers.

4. In a machine of the class described, a pipe-supporting frame, a pipe-gripping device, a lever fulcrumed on the frame and connected with the pipe-gripping device for reciprocating the same, and means on the gripping device engaged by the frame to rotate said device during its reciprocating 70 movement.

5. In a machine of the class described, a pipe-supporting frame, a lever removably connected therewith, a toggle-lever pipe-gripping device connected with the lever and adapted to straddle a pipe supported on the frame, and means on the gripping device engageable by the frame to rotate said device during longitudinal movement 75 thereof.

In testimony whereof I have hereunto subscribed my name in the presence of two witnesses.

NILS ANDERSON.
